UNITED STATES PATENT OFFICE.

JOHN H. BARRETT, OF CLEVELAND, OHIO.

REMOVABLE SADIRON STAND.

Application filed February 5, 1921. Serial No. 442,675.

To all whom it may concern:

Be it known that I, JOHN H. BARRETT, a citizen of the United States, residing at Cleveland, in the county of Cuyahoga and State of Ohio, have invented certain new and useful Improvements in Removable Sadiron Stands, of which the following is a specification.

This invention relates to removable sad-
iron stands, and has for its principal object
to provide a stand, which is easily attached
to or detached from an ironing board for
supporting a hot sad-iron without danger
of fire.

Another object of the invention is to pro-
vide a sad-iron stand of such simple con-
struction that the greater part thereof may
be stamped from plate material.

A further object of the invention is to
provide a stand for supporting a hot sad-
iron on a level with the ironing board and
conveniently slid therefrom onto the
stand.

With the above and other objects in view
as will be readily understood, the invention
will be hereinafter fully described as
illustrated in the accompanying drawings,
and the novel features thereof will be dis-
tinctly pointed out in the appended claim.

In the drawings similar characters of
reference are used to designate correspond-
ing parts.

Figure 1 is a plan view of a sad-iron stand
constructed in accordance with my invention
and applied to an ironing board.

Fig. 2 is a section, on an enlarged scale,
taken on line 2—2 of Fig. 1,

Fig. 3 is a similar view taken on line 3—3
of Fig. 1,

Fig. 4 is a face view of the flange of the
bracket, and

Fig. 5 is a view looking at the underside
of the bracket.

Referring to the drawings, 1 represents
the rear end portion of an ironing board or
table, to which is securely fixed a bracket
stamped from plate material and consisting
of a top side 2 and a flange 3 turned down at
a right angle thereto. A single screw at 4
fixes said bracket to the ironing board. The
flange 3 of the bracket is turned rearwardly
at 5 and then inwardly at 6, and is provided
with openings 7 and 8, which extend into and
form with openings 9 and 10 of the top side
2 of the bracket, sockets for receiving legs

11 and 12 of a frame 13, to which is fixed
a shelf 14 for supporting a sad-iron. The
frame 13 is constructed of a single piece of
heavy wire, and from the legs 11 and 12 ex-
tend horizontal arms 15 and 16 having their
upper sides level with the top side 2 of the
bracket. Said arms are bent downwardly at
a right angle at 17 and 18 and then hori-
zontally into a rectangular form consisting
of sides 19 and 20 and a rear side 21. The
shelf 14 is made to conform to a sad-iron
and is stamped from a plate which is turned
up and rolled over at its edges, as indicated
at 22, so that the shelf rests upon the
rectangular portion of the frame 13 and
its edges lie in the same horizontal
plane as the upper sides of the arms
15 and 16 of said frame and the top side 2 of
the bracket. Openings are provided in the
edges 22 of the shelf at 23 and 24 for re-
ceiving the downwardly bent portions 17
and 18 of the frame 13. The shelf 14 is de-
pressed at 25 of a size to come within the rec-
tangular portion of the frame 13, and lugs
indicated at 26 are stamped from said de-
pressed part of the shelf for bending around
the sides 19 and 20 and the rear side 21 of
said frame to fix the shelf thereto.

From the description and drawings, it is
obvious that this sad-iron stand is of sim-
ple and inexpensive construction, is capable
of being made for the most part from
stamped material, is easily attached to and
detached from an ironing board, the sad-iron
may be conveniently slid thereunto from
the ironing-board, and there is no danger
of fire from a hot sad-iron.

Having fully described my invention,
what I claim is:

A sad-iron holder comprising a plate 95
forming a shelf, the outer portion of the
plate bent upward and then outward and
downward, a frame attached to the under-
side of the plate and provided with hori-
zontal arms, the outward ends of which ex-
tend downward at right angles, a bracket
having means to attach it to an ironing board
and having holes to receive the ends of said
arms, the upper surfaces of the arms,
the bracket, and the marginal portion of the 100
shelf lying in substantially the same hori-
zontal plane.

In testimony whereof I affix my signature.

JOHN H. BARRETT.
